TOY TAPE RECORDER

Robert L. Lindsay, Hamilton, Ohio, assignor to Kenner Products Company, Cincinnati, Ohio, a corporation of Delaware

Filed Nov. 14, 1968, Ser. No. 14,472

Term of patent 14 years

Int. Cl. D21—02

U.S. Cl. D34—15

The broken line showing a tape cartridge in FIGURES 1, 2 and 3 is for illustrative purposes only.

I claim:

The ornamental design for a toy tape recorder, substantially as shown and described.
